UNITED STATES PATENT OFFICE.

WILLIAM WURDACK, OF ST. LOUIS, MISSOURI.

ELECTRIC-METER AND PANEL-BOARD CABINET.

1,041,398.

Specification of Letters Patent.

Patented Oct. 15, 1912.

Application filed October 19, 1910. Serial No. 587,909.

To all whom it may concern:

Be it known that I, WILLIAM WURDACK, a citizen of the United States, residing at the city of St. Louis, State of Missouri, have 5 invented a certain new and useful Electric-Meter and Panel-Board Cabinet, of which the following is a specification, reference being had to the accompanying drawings, forming a part hereof, in which—

13 Figure 1 is a top plan view of my new electric-meter and panel-board cabinet; Fig. 2 is a vertical sectional view therethrough on the line 2—2; Fig. 1; Fig. 3 is a top plan view thereof with the cover or top removed, showing the meter, panel-board, and the electrical connections or wiring therebetween; Fig. 4 is a sectional view on the line 4—4, Fig. 3; and Fig. 5 is a bottom plan view of the panel-board.

20 This invention relates to a certain new and useful electric-meter and panel-board cabinet, the objects of my invention being to provide a cabinet or box in which a meter and a panel-board, the panel-board comprising, as is usual, the main fuses, main switch, and distributing circuits, may not only be conveniently arranged closely adjacent each other and electrically connected in operative relation, but in and by which also the meter and all parts of the circuit within the cabinet and ahead of the meter are protected and prevented from being tampered with by unauthorized persons; to provide in an electric-lighting or other circuit an auxiliary 25 switch and fuses adapted to be thrown or cut into and complete the circuit on an interruption or blowing of a main fuse therein; to improve generally upon the construction of panel-boards; to provide a cabinet 30 of the kind stated with a cover adjustable relatively thereto; and to simplify and improve generally upon electric meter and panel-board cabinets and upon not only the arrangement of the electric-meter and panel-board in an electric-lighting or other circuit, but also the wiring or other electrical 35 connections therebetween.

With these objects in view, my invention resides in the novel construction of the 40 several parts thereof and in the novel arrangement and combination of the same, all as will hereinafter be described and afterward pointed out in the claims.

My new meter and panel-board cabinet 45 and the arrangement therein of the meter, panel-board, and wiring therebetween is

shown and will be described herein in connection with an electric-circuit adapted for lighting purposes; but it is to be understood that the same might equally well be 60 employed in connection with an electric-circuit adapted for other purposes.

In the drawings, wherein like reference characters or numerals refer to like parts throughout the several views, 1 indicates the 65 cabinet-box, which may be of any suitable material, preferably sheet metal, and which comprises a bottom-wall 2, end-walls 3—3', and side-walls 4—4'. A suitable cover or top 5 is adapted to be preferably removably 70 and adjustably secured to said box 1, as hereinafter more fully described. Box 1 is adapted to be arranged preferably in the wall of a building, as shown in Figs. 1 and 2, with the outer edges of its said end and 75 side walls substantially flush with the surface thereof.

Arranged preferably in the upper portion of box 1, as shown particularly in Figs. 2 and 3, and secured to said bottom-wall 2 in 80 any suitable manner, as by screws 6^a, is a preferably wooden tablet or slab 6, upon which an electric-meter 7 of any approved construction and having the usual dials 7^a is adapted to be suitably arranged and secured. This wooden tablet or slab 6 is preferably of such a size as to accommodate 85 meters of varying kinds and construction.

Arranged preferably in the lower portion of box 1, as shown particularly in Figs. 2 90 and 3, is a preferably slate tablet or slab 8, said tablet or slab 8 resting upon, and being preferably spaced from said bottom-wall 2 by, suitable perforated spacing-bosses 9 and being secured to, and held in proper position on, said bosses preferably by means of screws 9^a. It will be noted that the openings in said slab 8 for said screws 9^a are preferably of somewhat greater diameter than the diameter of said screws 9^a, so that slab 8 100 may be adjustably arranged with its sides plumbed in proper position in box 1. Mounted in any suitable manner preferably on the lower portion of said tablet 8 are a plurality of pairs of lamp-circuit fuse-plug 105 sockets 10 of any suitable construction, in and with which sockets are adapted to fit and coöperate suitable fuse-plugs of any suitable construction. These fuse-plugs, or fuses, as they might properly be called, are 110 likewise arranged and operate in pairs, and for convenience of reference, I have num-

bered the same 12—12^a, 13—13^a, 14—14^a, and 15—15^a. I have shown herein my new cabinet and the arrangement therein of the meter, panel-board, and wiring therebetween in connection with a three-wire system of distribution with four lamp-circuits, there being accordingly four pairs of said lamp-circuit fuses; but it will further be understood that my new cabinet and arrangement there-
in of the meter, panel-board, and wiring therebetween could equally well be adapted for use in connection with a two or any other wire system of distribution and with more or less lamp-circuits than the number thereof herein shown. Arranged on said tablet 8 preferably above said sockets 10 is a main switch 16 and also an auxiliary switch 17, for purposes hereinafter appearing. These switches 16 and 17 are prefer-
ably double-pole snap-switches of any ap-
proved construction and are arranged on tablet 8 preferably side by side, as shown particularly in Fig. 3. Arranged on said tablet 8 preferably above said switches 16
and 17, as shown particularly in Fig. 3, and secured to said tablet in any suitable manner, are a plurality of main fuse-plug sockets 18 preferably similar to said sockets 10, in and with which sockets 18 are adapted to fit
and coöperate main-fuse-plugs or fuses which are also preferably similar to said lamp-circuit fuse-plugs or fuses hereinbefore mentioned. In the system of electrical distribution herein shown, there are prefer-
ably five said main sockets 18 and likewise five said main fuse-plugs or fuses—one pair 19—19^a for the main switch 16, one pair 20—20^a for the auxiliary switch 17, and one 21 for the neutral line wire N. It will be
understood that, while I have herein shown and prefer to use fuses of the plug type as described, any other suitable type of fuse might be used in lieu thereof.

22 indicates a main bus bar which extends preferably centrally along tablet 8 between said switches 16 and 17 and said main and auxiliary fuse-sockets, as shown particularly in Fig. 3, being electrically connected to said fuse 21 and its socket 18 and, at its upper end, being preferably provided with a suitable terminal 23. With this terminal 23, said neutral line wire N is suitably electrically connected, this wire N leading to the service mains (not shown), as is well understood.

24 indicates a small bus bar extending laterally of, and electrically connected to, said main bus bar 22, this bus bar 24 communicating electrically through, say, fuses 12 and 14 with, respectively, lamp-circuit wires A and B, see particularly Fig. 3. And 25 indicates a similar bus bar likewise extending laterally of, and electrically connected to, said bus bar 22, this bus bar 25 communicat-
ing electrically through fuses 13 and 15 with,

respectively, lamp-circuit wires C and D. Additional bus bars may be similarly ar-
ranged and connected for additional lamp-
circuits, as will be obvious.

L and L' indicate the line wires leading 70 from the service mains and electrically con-
nected, respectively, to suitable terminals 26 and 26' suitably arranged on, and prefer-
ably at opposite sides of, said tablet 8, see parti-
cularly Fig. 3. Terminal 26 is pref- 75
erably electrically connected to main fuses 19 and 20, and terminal 26' is preferably electrically connected to main fuses 19^a and 20^a, see particularly Figs. 3 and 5.

The meter 7 and the panel-board comprising said tablet 8, and said main and auxiliary switches and said main and lamp-circuit or distributing fuses mounted thereon preferably as described, being arranged in box 1 also preferably as described, the cir- 80
cuit to the meter is preferably completed as follows, referring now particularly to Figs.
3 and 5: On one side, from wire L and its
said terminal 26, through fuse 19, through
wire 27 to terminal 28 of main switch 16, 90
then across said switch, the switch being
turned or snapped to "On" position, to di-
agonally opposite terminal 28^a thereof,
through wire 29 to a suitable terminal-block
30 arranged on and secured to tablet 8 pref- 95
erably near the upper end thereof, through
primary-wire terminal 30^a preferably re-
movably secured to block 30, and then
through primary wire 31; on the other side,
from wire L' and its said terminal 26', 100
through fuse 19^a, through wire 27' to termi-
nal 28^b of main switch, then across said
switch, the switch being turned or snapped
to "On" position, to diagonally opposite
terminal 28^c thereof, through wire 29' to a 105
suitable terminal-block 30' arranged on and
secured to tablet 8 preferably near the up-
per end thereof, through primary-wire ter-
minal 30^b preferably removably secured to
block 30', and then through primary wire 110
31'. From meter 7 the current is led or dis-
tributed by secondary wires 32 and 32',
through, respectively, terminals 33 and 33'
and terminal-blocks 34 and 34', said termi-
nals and terminal-blocks being preferably 115
similar to said terminals 30^a and 30^b and ter-
minal-blocks 30 and 30' and likewise simi-
larly arranged on said tablet 8, to lamp-cir-
cuit fuses 12^a and 13^a on one side and to
lamp-circuit fuses 14^a and 15^a on the other, 120
the current then flowing from fuses 12^a and
13^a, on one side, through wires A' and C' to
the lamps (not shown), and then back
through wires A and C to neutral wire N,
and from fuses 14^a and 15^a, on the other 125
side, through wires B' and D' to the lamps
(not shown), and then back through wires
B and D to the neutral wire N, as will be
well understood. It is obvious that addi-
tional lamp-circuits could likewise be pro- 130

vided for, if desired. Now, ordinarily or normally the auxiliary switch 17 and its fuses 20—20^a are not thrown into or included in said circuit, said switch being normally in "Off" position. However, should one of said fuses 19 or 19^a blow and the circuit be thereby interrupted, then said auxiliary switch 17 is snapped to "On" position and cut into the circuit, when said circuit will now be completed, on one side, from said wire L and its terminal 26, through fuse 20, through wire 36 to terminal 37 of auxiliary switch 17, then across said switch to diagonally opposite terminal 37^a thereof, through wire 38 to terminal 28 of main switch 16, and then to the meter as hereinbefore described, and, on the other side, from wire L' and its terminal 26', through fuse 20^a, through wire 36' to terminal 37^b of auxiliary switch 17, then across said switch to diagonally opposite terminal 37^c thereof, through wire 38' to terminal 28^b of main switch 16, and then to the meter as hereinbefore described. Thus, when said main switch 16 is in "On" position and said auxiliary switch 17 is in "Off" position, it will clearly be indicated to the user that only main switch 16 is closed and its fuses 19—19^a in service; when, however, both switches are in "On" position, it will further be clearly indicated to the user that both switches are closed and auxiliary fuses 20—20^a in service.

Cover 5 hereinbefore mentioned is provided at its sides with a suitable border or trim 39 adapted to project, when the cover 5 is in position, over and beyond the end and side walls of box 1. This cover 5 is also preferably made-up of or comprises two portions—an upper portion 40 and a lower portion 41, said upper portion 40 projecting outwardly beyond the plane of portion 41 to accommodate meter 7, as clearly shown in Fig. 2, and being provided with a section of glass 42 through which the meter-dials 7^a may be easily read, and portions 40 and 41 being provided with meeting shouldered ends, as at 43, where said portions are releasably secured and held together in any suitable manner, as by means of a screw or bolt 43' and its coöperating nut 43''. Near its upper end, lower portion 41 of cover 5 is provided with a suitable opening adapted to be removably closed by a suitable door 44 hinged to said portion 41, as at 44^a, and through which opening access may be had to said main fuses hereinbefore referred to when said door 44 is in open position. This door 44 is provided preferably with a small slot or opening, as at 44^b, through which, when said door is in closed position, a suitable staple 45 on said portion 41 is adapted to pass, this door 44, for purposes herein-after appearing, being preferably releasably sealed in closed position, as by means of a suitable seal 46. Below said door 44, this lower portion 41 of cover 5 is provided with suitable openings, as at 47 and 47', to accommodate, respectively, said main and auxiliary switches; and below said switch-openings, this lower portion 41 of cover 5 is further provided with another suitable opening adapted to be removably closed by a suitable door 48 hinged to portion 41, as at 48^a, and through which opening access may be had to said lamp-circuit fuses hereinbefore referred to when door 48 is in open position, this door 48 being preferably releasably held in closed position by means of a suitable catch or latch 49, as shown clearly in Figs. 1 and 4.

Now, while, as before stated, box 1 is adapted to be preferably arranged in a wall with the outer edges of its end and side walls flush with the surface thereof, the box being disposed preferably vertically relatively to said wall, at times, due to faults or irregularities in construction, the said box may be so arranged in said wall as not to be exactly vertically disposed relatively thereto or the outer edges of its said end and side walls may perhaps be below and not flush with the surface of said wall. For this reason, and in order that a neat appearance may be had when cover 5 is in closed position over said box, cover 5 is adapted to be preferably adjustably secured in proper position and, for this purpose, is provided near its sides with a plurality of angle members or brackets 50 adapted to be not only adjustably secured to cover 5, but also adapted to be adjustably secured to the end and side walls of box 1. As said angle members or brackets 50 and their manner or mode of attachment are similar, the construction of but one thereof and its mode or manner of attachment will be here described, referring now particularly to the lower part of Fig. 2. The upwardly-extending leg or portion 50' of said angle-bracket 50 there shown is normally loosely secured to cover 5 by means of a suitable bolt 51 and its coöperating nut 52, the opening for said bolt 51 through said leg being of somewhat greater diameter than the diameter of said bolt, whereby, as will be clear, cover 5, when placed in position, may be moved around or laterally adjusted, as it might be said, to proper position to neatly fit preferably exactly vertically disposed relatively to said wall, nut 52 being afterward screwed down on its bolt 51 to lock said cover in such position. The other or inwardly-extending leg 50'' of said angle-bracket 50 is provided with an elongated slot, as at 53, through and with which a suitable bolt 54 is adapted to pass and coöperate, whereby, as will also be clear, said cover 5 may be adjusted outwardly to fit closely against said wall should the outer edges of said end and side walls of box 1

be not flush with the surface thereof, a suitable nut 55 on said bolt 54 being screwed down to lock said cover 5 in such adjusted position. With said cover 5 arranged in 5 position as described, it will clearly be seen that the meter, said panel-board, and the electrical connections or wiring therebetween are fully protected, and to prevent the meter and all parts of the circuit within the cabinet 10 and ahead of the meter being tampered with by unauthorized persons, cover 5 is preferably releasably sealed in such closed position by means of suitable seals 56 arranged on said bolts 51. Now, should any 15 particular lamp-circuit become interrupted by the blowing of the fuse or fuses therein, the door 48 may be readily opened by the person in whose house or building the cabinet may be arranged, the blown fuse removed, and a new fuse placed in position. It will be noticed that, even with door 48 in 20 open position, the said switches being arranged as shown, access can not be had to the meter or to parts of the circuit within the cabinet and ahead of the meter. Should, however, the main-switch-circuit be interrupted by the blowing of one of said main fuses 19 or 19^a, door 44 being sealed in closed position so that the blown fuse can not be 25 removed by such person, auxiliary switch 17 is now turned or snapped to "On" position, thereby bringing into service said auxiliary fuses 20 and 20^a and completing the circuit as hereinbefore described. The person 30 authorized to open door 44 being now notified of the blowing of such main fuse, such authorized person in due time removes seal 46, opens door 44, removes the blown fuse and places a new fuse in position, and 35 then snaps auxiliary fuse 17 to "Off" position, door 44 being afterward closed and sealed in such position as before. It will further be noted that, should it be desired to test the meter, nut 43" may be unscrewed 40 from its bolt 43 and seal 56 and nut 52 removed from bolt 51 by an authorized person, when upper portion 40 of cover 5 may be readily removed and, the meter and panel-board being arranged in box 1 as shown, the 45 50 meter-terminals are easily accessible for such purpose.

I am aware that minor changes in the arrangement, construction, and combination of the several parts of my invention 55 may be made and substituted for those herein shown and described without departing from the nature and principle of my invention.

Having thus described my invention, what 60 I claim and desire to secure by Letters Patent is:

1. A cabinet of the kind stated comprising a box-shaped body-portion open at its top, a detachable sectional cover fitting 65 thereover and adapted to close the open top

thereof, and adjustable cover-holding means arranged within said body-portion and removably secured directly to both said body-portion and said cover, said means being adapted to permit of either lateral or perpendicular, or both lateral and perpendicular, adjustment of said cover relatively to said body-portion and to also detachably hold said cover in closed adjusted position on said body-portion; substantially as described. 70 75

2. A cabinet of the kind stated comprising a box-shaped body-portion open at its top, a detachable sectional cover fitting thereover and adapted to close the open top thereof, angle-brackets within said body-portion, and securing-means extending from within said body-portion through said body-portion and cover to the exterior and removably securing said angle-brackets directly to said body-portion and to said cover, 80 said angle-brackets being adapted to permit of either lateral or perpendicular, or both lateral and perpendicular, adjustment of said cover relatively to said body-portion 85 and said angle-brackets and securing-means being adapted to detachably hold said cover in closed adjusted position on said body-portion; substantially as described. 90

3. A cabinet of the kind stated comprising a box-shaped body-portion open at its top, a detachable sectional cover fitting thereover and adapted to close the open top thereof, angle-brackets within said body-portion and having one leg thereof provided 95 with an elongated slot and the other leg with an enlarged opening, and through-bolts fitting in said slots and openings of said angle-brackets and extending from within said body-portion through said body-portion and cover to the exterior and provided with securing-nuts on their outer ends, 100 said angle-brackets being adapted, on the loosening of said nuts, to permit of either lateral or perpendicular, or both lateral and perpendicular, adjustment of said cover relatively to said body-portion and said through-bolts and angle-brackets being 105 adapted, on the tightening of said securing-nuts against said body-portion and cover, 110 to detachably hold said cover in closed adjusted position on said body-portion; substantially as described. 115

4. The combination with an electric circuit comprising line-wires, main fuses, a 120 main switch, and distributing-circuits, of an auxiliary switch normally out of said circuit, but adapted to be cut into said circuit on the blowing of one of said main fuses, 125 said circuit being completed through both said switches when said auxiliary switch is cut thereinto; substantially as described.

5. The combination with an electric circuit comprising line-wires, main fuses, a main switch, and distributing-circuits, of 130

an auxiliary switch and auxiliary fuses normally out of said circuit, but adapted to be cut into said circuit on the blowing of one of said main fuses, said circuit being completed through both said switches when said auxiliary switch is cut thereinto; substantially as described.

6. The combination with an electric circuit comprising line-wires, main fuses, a main switch, and distributing-circuits, of an auxiliary switch and auxiliary fuses electrically connected to said line-wires and to said main-switch and normally out of said circuit, but adapted to be cut into said circuit on the blowing of one of said main fuses, said circuit being completed through both said switches when said auxiliary switch is cut thereinto; substantially as described.

7. A panel-board comprising a tablet, a plurality of main-fuses mounted thereon adapted to be electrically connected to the

line-wires of an electric circuit, a plurality of auxiliary main-fuses also mounted on said tablet adapted to be electrically connected to said line wires, a plurality of distributing-circuit-fuses also mounted on said tablet adapted to be electrically connected to distributing-circuit-wires, a main switch also mounted on said tablet and electrically connected to said main-fuses, and an auxiliary main switch also mounted on said tablet and electrically connected to said main switch and to said auxiliary main fuses; substantially as described.

In testimony whereof, I have signed my name to this specification in the presence of two subscribing witnesses.

WILLIAM WURDACK.
